UNITED STATES PATENT OFFICE.

HENRY F. REED AND SAMUEL KELLER, OF NEW YORK, N. Y.

DESIGN FOR A FOUNDATION-FRAME FOR A FLORAL PIECE.

SPECIFICATION forming part of Design No. 14,984, dated April 29, 1884.

Application filed December 7, 1883. Term of patent 7 years.

To all whom it may concern:

Be it known that we, HENRY F. REED and SAMUEL KELLER, both of the city, county, and State of New York, have invented and 5 produced a new and original Design for a Foundation for a Floral Ornament; and I do hereby declare that the following is a full and exact description thereof, reference being had to the accompanying drawing, and to the letters of reference marked thereon, making a part of this specification.

The accompanying drawing is a perspective view of our newly-designed open-work foundation for holding flowers.

15 The leading feature of our design is a broken or dismantled mill-wheel.

A in the drawing represents the broken wheel in skeleton form lying dismantled upon the base C.

20 B represents a mill-race of open-work, supported upon open trestles D, D, and E, an open-work structure representing the support for the outer bearing of the wheel.

F represents, in open-work, a mill-house, at 25 the base of which the wheel is placed.

The design is completed further by the open-work frame G in representation of a slope or bank under the race.

We claim—

1. The design for a foundation for an ornamental floral piece, herein shown and described, the same consisting of the open-work frame in the form of the broken or dismantled water-wheel A, lying upon a base, C, in combination with outer bearing, E. 30

2. The design for a foundation for an ornamental floral piece, herein shown and described, the same consisting of the open-work frame in the form of a water-wheel, A, lying broken or dismantled at the foot of a mill-race, 40 B, supported upon open trestles D D at the side of a mill-house, F. 35

In testimony whereof we have signed our names to this specification in the presence of two subscribing witnesses.

HENRY F. REED.
SAMUEL KELLER.
